TOOL

John William Slayton, Jr., Pittsburgh, Pa.

Application December 16, 1946, Serial No. 716,463

7 Claims. (Cl. 306—33)

1

This application relates to tools of the class which have a striking head and a handle to which the head is secured and by which the head is driven to strike a blow. Typical tools of this class are hammers, hatchets, axes, mallets, etc.

My invention is directed to means for holding the head on the handle in a secure manner. It is particularly useful for hammers, especially machinists hammers, and therefore will be described with reference thereto although it is to be understood that it can be used to great advantage in other tools of the class referred to.

In the accompanying drawings I have illustrated certain present preferred embodiments of my invention in which,

Figure 1 is a front elevation view of a hammer embodying my invention, a portion of the handle being removed;

Figure 2 is an end view of the hammer shown in Figure 1;

Figure 3 is a view similar to Figure 1 but with portions thereof shown in vertical section;

Figure 4 is a plan view with certain portions removed;

Figure 5 is a view similar to Figure 3 of a modification of my invention;

Figure 6 is a plan view of the hammer shown in Figure 5 with certain portions removed;

Figure 7 is a view similar to that in Figure 3 showing a second modification of my invention;

Figure 8 is a plan view of the hammer shown in Figure 7 with certain portions removed; and

Figure 9 is a vertical section on the lines IX—IX of Figure 7.

A hammer constructed in accordance with my invention comprises a head 11 having a striking face 12, a peening face 13 and an eye 14. As shown in Figures 4, 6 and 8, a rectangular-shaped recess 15 longer and wider than the eye is cut in the outer face of the head. A cap 16 fits within the recess extending beyond the sides of the eye 14. The cap is held in the recess by two screws 17. The hammer also has a handle 18, the outer end of which is inserted into the eye 14.

In the embodiment shown in Figures 1, 2, 3 and 4 of the drawings, the hammer further includes a wedge 19 which is inserted into the eye 14 between the end of the handle 18 which is within the eye and a side of the eye which is generally parallel to the striking face of the hammer. As shown in Figure 3 the wedge increases in thickness from the outer to the inner face of the head and is bent over at its outer end to form a laterally extending flange 20. As shown in Figures 1

2

and 2 the depth of the recess 15 is increased at one end to accommodate the flange 20.

One side of the outer end of the handle 18 is shaped so that it will contact the wedge 19 throughout the full length of the wedge. A leaf spring 21 is placed between the cap 16 and the end of the handle 18 and curved so that when the cap 16 is in place the spring 21 continuously presses the handle 18 inwardly against the wedge 19. The spring thus compensates for any shrinkage which may occur in the handle during use.

Figures 5 and 6 show a hammer which is generally similar to the one shown in Figures 1 to 4. In addition, however, it has a second wedge 22 which is placed between the handle 18 and a side of the eye opposite from the wedge 19. This second wedge 22 decreases in thickness from the outer to the inner faces of the head 11, but its slope is considerably less than the slope of the wedge 19 so that the head 11 cannot slip off the handle 18 after the hammer is assembled. The outer end of the wedge 22 carries a leaf spring 23 which presses downwardly against the handle 18 and thus holds the handle against the wedge 19. Both wedges 19 and 22 are held within the eye by the cap 16.

As shown in Figures 4 and 6, the two sides of the eye which extend across the head 11 in a direction generally parallel with the striking face 12 of the hammer are not of the same width, the side nearest the striking face being wider so that the other two sides 24 converge towards each other. The end of the handle 18 which fits within the eye is shaped so as to conform to the slope of the sides 24. Inward pressure of the handle 18 against the wedge 19, which is caused by the cap 16 and the spring 21, also wedges the handle 18 against the sides 24 and thus further insures a tight secure fit of the handle within the eye.

In the embodiment shown in Figures 7, 8 and 9, the eye 14 does not have the converging sides as described above in connection with Figures 4 and 6. To insure a tight fit between the handle 45 and the eye a wedge 25 is inserted in a plane generally at right angles to the wedge 19. The thickness of this wedge increases from the outer to the inner faces of the wedge as does the wedge 19. The outer end of the wedge is bent over to form a flange 26 which is held between the head 11 and the cap 16, the depth of the recess 15 being increased along one side to accommodate this flange. A side of the outer end of the handle 18 is notched as shown at 27 to 50 accommodate the wedge 25 and thus avoid the 55

head being carried slightly off center on the handle 18.

The manner of assembling all three embodiments is generally the same. The handle 18 is inserted into the eye from the inner face of the head until it extends beyond the head. The wedge 19 is placed against the end of the handle 18. The wedge and the handle are then pulled together into the eye. The spring 21 is placed against the end of the handle 18 and the cap 16 is screwed down in place against the spring 21. In the embodiment shown in Figures 5 and 6, the wedge 22 and spring 23 are placed against the handle 18 and brought down into the eye along with the wedge 19 and handle 18. In the embodiment shown in Figures 7, 8 and 9, the wedge 25 is placed against the side of the end of the handle 18 and brought down into the eye with the wedge 19 and handle 18.

From the foregoing description it is apparent that I provide a means for holding the head of a hammer on a handle in a secure and relatively permanent manner. At the same time the head may be readily removed should it be desirable to do so. It is not necessary to drive wedges into the handle as has heretofore been customary to secure a head to a handle. It is thus possible to impregnate the end of the handle to reduce shrinkage of the handle within the eye. If wedges are driven into the handle end, it is not feasible to impregnate the handle because the brittle portion of the handle splits and the splits are carried along a substantial length of the handle.

The head of a hammer embodying my invention does not require as deep an eye as those utilizing prior methods of securing a head to a handle, and therefore the portion of the head around the eye does not have to be as deep as prior hammers. This permits the manufacture of hammer heads by machining from standard bar stock instead of by the more expensive method of forging which has heretofore been used. Machining the heads makes closer manufacturing tolerances possible than with forging, and individual fittings of a handle to a head are avoided. Thus mass production methods of manufacture may be used.

Although I have described certain present preferred embodiments of my invention, it is to be understood that it may be otherwise embodied within the scope of the following claims.

I claim:

1. A tool of the class described comprising a head having an eye, a handle one end of which can be inserted into said eye, a wedge between said end and said eye, the wedge increasing in thickness from the outer to the inner face of the head, one side of said handle end having a sloping face cooperating with said wedge, and resilient means for applying pressure between the wedge and the handle end.

2. A tool of the class described comprising a head having an eye, a handle one end of which can be inserted into said eye, a wedge between said end and said eye, the wedge increasing in thickness from the outer to the inner face of the head, one side of said handle end having a sloping face cooperating with said wedge, resilient means for pressing said handle end inwardly against the wedge, and means for holding said wedge in the eye.

3. A tool of the class described comprising a head having an eye, a handle one end of which

can be inserted into said eye, a wedge between said end and said eye, the wedge increasing in thickness from the outer to the inner face of the head, one side of said handle end having a sloping face cooperating with said wedge, a cap extending across the outer end of the eye and secured to the head to hold the wedge in the eye and a spring between said cap and said handle end for pressing the handle against the wedge.

10 4. A tool of the class described comprising a head having an eye, the sides of the eye being parallel to its central axis, a handle one end of which can be inserted into said eye, a wedge between said end and said eye, the wedge increasing in thickness from the outer to the inner face of the head, one side of said handle end having a sloping face cooperating with said wedge, a cap extending across the outer end of the eye and secured to the head to hold the wedge in the eye.

20 5. A tool of the class described comprising a head having an eye, a handle one end of which can be inserted into said eye, one of the two sides of the eye which extend across the head being wider than the other such side, a wedge between said handle end and the wider of the two said sides of the eye, the wedge increasing in thickness from the outer to the inner face of the head, the outer end of the handle being shaped to fit within the eye and to cooperate with the wedge, and resilient means for applying pressure between the wedge and the handle end.

25 6. A tool of the class described comprising a head having an eye, a handle one end of which can be inserted into said eye, a wedge between said handle end and one side of said eye, the wedge increasing in thickness from the outer to the inner face of the head, a second wedge between said handle end and the side of the eye opposite to that in contact with the first wedge, said second wedge decreasing in thickness from the outer to the inner face of the head, a spring secured to said second wedge and arranged to press inwardly on the handle end, and means for holding both wedges in the eye.

30 7. A tool of the class described comprising a head having an eye, a handle one end of which can be inserted into said eye, a wedge between said handle end and said eye, the wedge increasing in thickness from the outer to the inner face of the head, a second wedge between said handle end and said eye and in a plane generally at right angles to the first wedge, said second wedge also increasing in thickness from the outer to the inner face of the head, two sides of said handle end being sloped to cooperate with said wedges and means for holding both wedges in the eye.
